UNITED STATES PATENT OFFICE.

FRANK S. JARRETT, OF UPPER DARBY TOWNSHIP, DELAWARE COUNTY, PENNSYLVANIA.

DESIGN FOR A FLOOR LAMP.

Application filed December 19, 1925. Serial No. 15,786. Term of patent $3\frac{1}{2}$ years.

To all whom it may concern:

Be it known that I, FRANK S. JARRETT, a citizen of the United States, and a resident of Upper Darby Township, county of Delaware, and State of Pennsylvania, have invented a new, original, and ornamental Design for Floor Lamps, of which the following is a specification, reference being had to the accompanying drawing, forming a part thereof.

In the drawings Figure 1 is a perspective view of the lamp with the ornamental features, shown in detail in Figures 2 and 3, omitted; Figure 2 is a fragmentary view of the upper portion of the lamp; and Figure 3 is a fragmentary view of the lower portion of the lamp.

I claim:

The ornamental design for a floor lamp, substantially as shown.

FRANK S. JARRETT.
